US0D1074692S

(12) United States Design Patent (10) Patent No.: US D1,074,692 S
(45) Date of Patent:  May 13, 2025

(54) DISPLAY SCREEN WITH GRAPHICAL USER INTERFACE

(71) Applicant: IGT, Las Vegas, NV (US)

(72) Inventors: Stephanie Quiles, Las Vegas, NV (US);
Derick Rougeau, Las Vegas, NV (US);
Steve Richardson, Las Vegas, NV (US)

(73) Assignee: IGT, Las Vegas, NV (US)

() Term: 15 Years

(21) Appl. No.: 29/809,890

(22) Filed: Sep. 30, 2021

(51) LOC (15) Cl. 14-04

(52) U.S. Cl.

USPC D14/485
